UNITED STATES PATENT OFFICE.

CHARLES E. VAN NORMAN, OF SPRINGFIELD, MASSACHUSETTS, ASSIGNOR TO VAN NORMAN MACHINE TOOL COMPANY, OF SPRINGFIELD, MASSACHUSETTS, A CORPORATION OF MASSACHUSETTS.

GRINDING MACHINE.

Application filed October 6, 1921. Serial No. 505,893.

To all whom it may concern:

Be it known that I, CHARLES E. VAN NORMAN, citizen of the United States, residing at Springfield, in the county of 5 Hampden and State of Massachusetts, have invented new and useful Improvements in Grinding Machines, of which the following is a specification.

This invention relates generally to improvements in machine tools and more particularly to machines which embody the characteristics of both a grinder and a lathe.

The invention is an improvement on that 15 disclosed in U. S. Letters Patent No. 1,445,875, granted February 20, 1923 on an invention of Robert W. Ellingham and Charles E. Van Norman.

The object of this invention is to provide, 20 in a machine of the general class disclosed in said patent, an improved arrangement of the driving mechanism, whereby one electric motor carried by one of the relatively movable heads of the machine is connected to 25 drive both of the rotary spindles in said heads, characterized by the use of a flexible shaft, or equivalent connection, to drive the rotary spindle in the other head.

Other features and advantages will appear in the following description and in 30 the illustrative embodiment of the invention in the accompanying drawings, in which,— Fig. 1 is a front elevational view of a machine embodying the invention;

Fig. 2 is a top plan view thereof;

Fig. 3 is a fragmentary top plan view of the wheel trimmer.

Fig. 4 is an enlarged end elevational view 40 showing the speed-reduction mechanism and change speed gearing, with means for disconnecting them from the work-holder.

Referring to these drawings; the machine includes a suitable base 15, which as shown is adapted to be mounted on a bench al- 45 though it may be otherwise supported if desired. The particular construction of base 15 is not important except that it should preferably directly underlie the two heads which it supports and be of suffi- 50 ciently sturdy construction and rigidity to support the heads without undue vibration of the latter when the machine is in opera-

tion. With the particular arrangement chosen for these heads, the bed is of substantially right angular shape in plan.

Supported from bed 15 are two heads 16 and 17, one of which, as 16, will be hereinafter referred to as the wheel-head and the other of which, as 17, will be hereinafter referred to as the work-head. In each of these heads is mounted a rotatable spindle,—the spindles for the heads 16 and 17 being designated at 18 and 19 respectively. One of these spindles, as 18, carries a suitable grinding wheel, such as 20, the size and shape of which will, of course, be varied according to the nature of the work to be performed. Provision is also made on the wheel-head 16 for the reception of lathe tools,—a socket 22 being provided at the forward end of the wheel-head to receive a tool-holder, which may be clamped in place by set screws 24. The other spindle 19 is designed to carry some suitable device for supporting and driving the work, herein- 70 after referred to as a work-holder. For certain classes of work, a tail stock 26, carrying an ordinary dead center 27, is provided to cooperate with the work head 17, which then serves as a head stock, to support the work on centers.

The particular manner of mounting the heads 16 and 17 on base 15 is, according to many features of the invention, unimportant and may be varied in many ways and still embody the invention. The essential thing, with respect to the mounting of these heads, is provision for relative longitudinal movement and transverse cross-feeding movement between the wheel-head and work-holder. Both these movements might be effected by movement of either one of these heads or one movement might be accomplished by each. As an illustrative example of one of many mountings available, the work-head 17 is carried on a bed or carriage 28 which is mounted to slide longitudinally on ways 29 on base 15 and may be moved by any suitable means, as by means of a rotatable hand-wheel 30 and suitable intermediate connections well-understood in the art. The wheel-head 16 is mounted to slide on ways 31 in a direction transverse to the line of travel of carriage

28 and may likewise be moved by any suitable mechanism, of which there has been exemplified a rotatable hand-wheel 32 which through means well-known in the art may move head 16 for cross-feeding purposes. Since the invention is independent of the particular means for moving the heads 16 and 17, they may be operated in any suitable way appropriate for the purpose.

10 Aside from the provision for the two relative movements above-described, it is desirable according to some features of the invention, to provide, either in conjunction with or independent of them, an arrangement which will permit oscillation of one of the heads, as for example the work-head 17. Thus, the latter, as shown, is movable, relatively to its supporting carriage 28, about a vertical stud 33, and may be adjusted to bring the axis of the work-holder at various angles to that of the wheel-carrying spindle 18. The head 17 may be clamped in its various positions of angular adjustment by a handle nut 36 threaded upon the upper end of stud 33. The angular adjustability of head 17 permits all sorts of taper turning and grinding and the head may equally well be mounted for mechanical oscillation for the purpose of grinding curved surfaces, 30 a full disclosure of mechanism for accomplishing this result and the slight changes in the mounting of the head being given in reissued Letters Patent of the United States No. 13,892 granted March 16, 1915 to 35 Charles E. Van Norman. Reference to this patent is also made for a disclosure of a means for automatically effecting the longitudinal and transverse movements above described.

40 The tail stock 26, heretofore described, is mounted on the carriage 28 for longitudinal adjustment and may be clamped in various positions of adjustment by means of a handle nut 37, all in a manner which is analogous 45 to the mounting of a tail stock in a lathe and is too well known in the art to require further description.

In accordance with this invention, one of the rotary spindles in one of the movable heads is driven from a suitable source of power through the intermediary of a flexible shaft which will permit relative movement between the head and source in any direction. Thus, as shown, the work-holder 55 spindle 19 is driven from an electric motor 38 through a flexible shaft, conventionally indicated at 39, and it will be noted that this shaft permits relative longitudinal, transverse and angular or oscillatory movements between the motor 38 and the work-holder. The flexible shaft, herein conventionally indicated, is too well known to require detailed description and illustration. Various other equivalent means for connecting the motor 38 and work-holder spindle

19 may be provided, as desired, to accomplish the result above described and by the term "flexible shaft," as hereinafter used, is meant, not only a continuous shaft which in itself is flexible, but also any interconnected parts or series of parts which include a provision for relative angular movement between some of the connected parts and which will transmit power from a suitable source and at the same time permit relative movement between the source and the member to which the power is transmitted.

70 Preferably, although not necessarily, according to all features of the invention, the motor 38 is utilized to drive the wheel-carrying spindle 18 and, to this end, the motor is shown as mounted for movement with the wheel head 16, as by being fastened thereto by bolts 40. The heads of the latter preferably engage in T-slots 41 on head 16 to 75 permit adjustment of the motor on the head. The shaft 42 of motor 38 carries a pulley 43 and a belt 44 connects this pulley to a pulley 45 on the wheel-carrying spindle 18, these pulleys being designed to give the desired speed ratio between the motor and spindle. Other pulleys, may, of course, be supplied which are interchangeable with those described to effect other speed ratios so that grinding wheels of various diameters 95 may be driven at the proper speeds. The mounting of motor 38 for movement with the wheel head eliminates the usual compensating devices customarily employed to permit movement of the wheel-head without interruption in the continuity of the drive. The elimination of these devices does away with a number of parts which ordinarily travel at very high speed and the elimination of each such part not only is advantageous, 100 in that it makes for simplification of the machine, but also because it contributes toward the reduction of vibration, freedom from which is essential for precise grinding.

105 Since motor 38, if of a standard type, rotates at considerably higher speed than that desired for the work holder spindle 19, it is essential to provide in the driving connections between the latter and the motor speed reduction mechanism and one suitable mechanism 110 for this purpose is shown in Figs. 3 and 4. As there shown, a worm gear 46 is fixed to spindle 19 and a worm 47 is provided to drive the gear. The worm 47 is fixed on a shaft 48 and the latter is mounted in suitable bearings provided in a tubular housing 49 which, as shown, is fixed to a casing 50 forming a housing for gear 46. This casing 50 is desirably mounted for adjustment on the work-head 17, as shown in Fig. 4. Thus, 115 casing 50 which encompasses spindle 19, is pivoted at one end to the work-head by a stud 51 and at the other end has a slot 52 through which a cap screw 53 passes for the purpose of clamping the casing to the head 120 130

in its various positions of adjustment. A screw 54 threaded into casing 50 projects into slot 52 and is designed to abut screw 53 to adjustably limit the upward movement 5 of casing 50 and prevent the worm 47 and gear 46 from being improperly intermeshed. By loosening screw 53, casing 50 will drop downwardly and disengage worm 47 from gear 46, so that the spindle 19 may be turned 10 over by hand to facilitate the mounting of work in the work-holder or may be held stationary when desired, as when grinding the teeth of a reamer, and then angularly adjusted by hand, as required.

15 It is also desirable that provision be made for changing the speed of the work-holder to secure proper surface speeds on work of varying diameters. To this end, a second shaft 55 is mounted above casing 50 in a 20 tubular upper housing 56 and in parallel relation with shaft 48. One end of the latter is connected to the corresponding end of shaft 55 by intermeshing spur gears 57 and 58, such gears being removable from their 25 shafts to permit others of different ratios to be substituted. The other ends of shafts 48 and 55 are adapted for connection to the flexible shaft 39, the latter being connectible with the former when the change gears 57 30 and 58 are not desired and with the latter when such gears are to be used. As an illustrative example of one means of connecting the flexible shaft 39 to either of the shafts 48 or 55, the stationary member of shaft 39,—its casing,—is connected by a 35 threaded coupling 59 to the end of either housing 49 or 56 and the rotatable element of the flexible shaft, indicated at 60, has a projection 61 which fits into a slot 62 formed 40 in shafts 48 and 55. The connection of shaft 39 to the shaft and casing of motor 38 may be effected in a similar manner.

45 For the purpose of trimming off the grinding wheel 20, whenever necessary or desired, a wheel-trimmer, consisting of a diamond point 81 fixed in a stem 82, is provided. The stem 82 is insertible into a socket 83 provided on the tail-stock 26 and projecting therefrom at right angles to the 50 axis of the dead center 27. A set screw 84 is provided to clamp stem 82 in its socket. To utilize this trimmer, the tail stock is moved on bed 28 into a position such that on 55 movement of the latter the trimmer will traverse the wheel and the grinding wheel 20 is set in motion, the head 17 being moved

by the means provided to feed the wheel to the trimmer.

The general operation of the machine is 60 analogous to ordinary grinders and is too well understood to require description here.

The invention has been disclosed herein, in an embodiment at present preferred, for 65 illustrative purposes, but the scope of the invention is defined by the appended claims rather than by the foregoing description.

What I claim is—

1. In a grinding machine, a base, a work head and a wheel head mounted thereon for movement one relatively to the other, rotary 70 spindles journaled one in each of said heads, a motor mounted to move with the wheel head, a pulley on one end of the motor shaft, driving connections from said pulley to the wheel head spindle, and driving connections 75 including flexible means connecting the other end of the motor shaft and the work head spindle.

2. In a grinding machine, a base, a work head and a wheel head mounted thereon for movement one relatively to the other, rotary spindles journaled one in each of said heads, a motor mounted to move with the wheel head, a pulley on one end of the motor shaft, driving connections from said pulley to the 80 wheel head spindle, and driving connections including flexible means and speed reduction mechanism connecting the other end of the motor shaft and the work head spindle.

3. In a grinding machine, a base, a work head and a wheel head mounted thereon for movement one relatively to the other, rotary spindles mounted one in each of said heads, a motor mounted to move with one of said heads, driving connections from said motor 90 to each of said spindles, the driving connection to one of said spindles including flexible means between the said motor and spindle.

4. In a grinding machine, a base, a work head and a wheel head mounted thereon for movement one relatively to the other, rotary spindles journaled one in each of said heads, a motor mounted to move with one of 100 said heads, driving connections from said motor to each of said spindles, the driving connections to the work head spindle including flexible means and speed reduction mechanism between said motor and spindle.

105 In testimony whereof I have affixed my 110 signature.

CHARLES E. VAN NORMAN.
